UNITED STATES PATENT OFFICE.

ARTHUR JAMES POLLEY, OF EARLSWOOD, AND FREDERICK GEORGE CREED, OF CROYDON, ENGLAND.

TYPE-SETTING AND PRINTING MACHINE.

1,321,329.

Specification of Letters Patent.

Patented Nov. 11, 1919.

Application filed April 28, 1919. Serial No. 293,372.

To all whom it may concern:

Be it known that we, ARTHUR JAMES POLLEY and FREDERICK GEORGE CREED, subjects of the King of Great Britain and Ireland, residing, respectively, Earlswood, in the county of Surrey, England, and Croydon, in the county of Surrey, England, have invented Improvements in Type-Setting and Printing Machines, of which the following

10 is a specification.

This invention relates to apparatus designed to reproduce in ordinary printed characters, columnwise, messages or intelligence (hereinafter referred to for brevity as words) transmitted in the form of electric impulses or which have been so transmitted and recorded as perforations in a tape.

In some kinds of apparatus of the last mentioned kind, the tape is perforated on what is known as the five unit system and in other kinds of such apparatus, the tape is perforated on the Wheatstone Morse system. Examples of apparatus of the last mentioned kind are described in the specifications of former British Letters Patent No. 22653 of 1902, No. 25861 of 1905, No. 8999 of 1907 and No. 1947 of 1908, granted to F. G. Creed and W. A. Coulson, but in these cases, the type carrying devices are each provided with only one ordinary type character, and only one ordinary type character is printed at one time.

Now the present invention has for its object to provide improved apparatus adapted to be operated or controlled by electric impulses, or by perforated tape, whereby ordinary type characters are selected from a magazine and assembled into a line of type which is then moved to a printing position prior to the type being broken up and redistributed.

Printing mechanism according to the invention may comprise a multi-channelled type magazine containing the different kinds of type to be used and also spaces (hereinafter included in the term type), type releasing or ejecting mechanism operated by or under the control of type selecting levers and adapted to permit selected type to pass one at a time from their respective receptacles, to line of type assembling means whereby released type plates are assembled in the form of a line of type representing one or more words with one or more spaces between words, a movable carrier for a line

of type, means for transferring a line of type from the assembling means to the said carrier, a platen for carrying a sheet of paper upon which the line of type is caused to print a line of words, means such as an inking ribbon or roller, for causing the line of type to produce an impression on the sheet of paper, means for moving the platen with sheet of paper relatively to the line of type so as to cause the latter to print a line of words on the sheet of paper, means for feeding the sheet of paper endwise so that successive lines of words can be printed in column form thereon, type distributing mechanism arranged above the magazine, carrier transferring means whereby the carrier with the line of type carried thereby, can, after it has printed a line of words, be brought into a position for the line of type to be transferred to the type distributing mechanism, means for transferring the line of type from the carrier to the distributing mechanism, and motor operated mechanism for actuating, at the required times, the various parts of the printing mechanism necessary for effecting the above mentioned operations.

Printing mechanism embodying the invention can be constructed in various forms and the parts thereof be arranged in various ways to effect the required result, and, as before indicated, be used in connection with various constructions of electric impulse or perforated tape controlled apparatus of the class hereinbefore referred to.

In the accompanying illustrative drawings, Figure 1 shows in front elevation and Fig. 2 partly in plan and partly in horizontal section one construction of column printing apparatus suitable for carrying the invention into practice. Fig. 3 shows partly in elevation and partly in cross section the left hand end of the apparatus and Fig. 4 shows partly in elevation and partly in cross section the right hand end of the apparatus. This printing apparatus is shown associated with selective apparatus of the kind herein referred to, for operating the type selecting levers used in the present invention.

Fig. 5 shows in plan, part of the type assembling means. Figs. 6 and 7 are sectional detail views at right angles to one another showing clutch mechanism for temporarily connecting a cam shaft to a constantly running secondary driving shaft. Fig. 8 is a plan and Fig. 9 a perspective view showing

apparatus for use in connection with the mechanism for controlling the clutch mechanism shown in Figs. 6 and 7. Fig. 10 shows in face view a type-plate. Fig. 11 is a similar view of a "space" plate. Fig. 12 is a section of one of these plates taken on the line $\alpha\alpha$ of Fig. 11.

In the examples shown, and referring more particularly to Figs. 1, 2 and 3, A is the magazine for holding the different kinds of type to be used in reproducing, in ordinary characters, messages or intelligence received as electric impulses, or in the form of perforations in a tape. B are the devices, herein called type selecting levers, for releasing the type, one by one, from the magazine, in accordance with the particular electric signals or sets of perforations in a tape, that have to be reproduced as ordinary printed characters. The line of type assembling mechanism is shown at C and the paper holding, feeding and printing mechanism is shown at D, both at the bottom of the machine. The mechanism for distributing the type, comprising each line of type, back into the magazine, after being used for printing, is shown at the top of the apparatus at E. The mechanism for transferring each line of type, after use, from the line of type assembling mechanism at C back to the type distributing mechanism at E, (Fig. 2) is shown at G.

In the particular example of column printing apparatus shown, such apparatus is assumed to be associated with apparatus of the type described in the specification of said British Letters Patent No. 1947 of 1908 granted to F. G. Creed and W. A. Coulson for reproducing, in ordinary characters, telegraphic or other messages or intelligence in the form of perforations in a tape. Such apparatus is hereinafter called for brevity, the "Creed selective apparatus." In the apparatus now being described, the type selecting levers B correspond to the levers g used for actuating the type carrying levers a shown in the drawings of the said former specification and are raised by the pistons of pneumatic motors the cylinders of which are formed by holes H (Fig. 2) formed in a block I, the piston rods of the motors being shown at J. Compressed air is admitted to the motor cylinders and released therefrom, by slide valves operated and controlled in the manner, and for the purpose described in the said former specification and further description thereof here will therefore be unnecessary. K is the main driving or cam shaft of the Creed selective apparatus. It is to be clearly understood however that devices corresponding to and having the function of the type selecting levers B, can be associated with and be actuated by apparatus other than the "Creed selective apparatus" and

though they may advantageously be associated with such apparatus, such devices are not limited to use therewith.

Associated with the driving shaft K of the Creed or other selective apparatus used, is a main driving shaft M and a secondary driving shaft N. The shafts K and M are geared together through bevel gearing O and P and connecting spindle R so as to rotate simultaneously at the same speed, and either of them may be driven from a motor, for example an electric motor, through a driving wheel S fixed to one of them, for example, the shaft M as shown. The shaft N is driven from the shaft M through worm gearing F. From these shafts K, M, N, the various movable parts of the column printing mechanism, which will now be described, are actuated as and when required, the shafts and other parts being mounted in suitable stationary bearings, and standards, indicated generally as T, carried by a base plate V.

The magazine A to contain the different kinds of type, is a multi-channeled magazine similar in construction to that used in other machines, as for instance that used in line of type casting machines, the magazine being arranged vertical with the type receptacles a (Fig. 3) therein, in a straight row and terminating at their lower ends at a suitable distance above a funnel shaped guide b (Fig. 1) having a doubly inclined bottom or support c upon which released type fall, one at a time, and pass to the type assembling means. The guide b may conveniently be divided, as shown, by curved ribs d into a number of channels e of different lengths extending from the lower ends of the type receptacles a and converging toward a centrally arranged outlet or guide channel e' below which is the type assembling means. The type, as shown in Figs. 10, 11 and 12, are each in the form of a flat plate f (hereinafter called a type plate) notched at its opposite vertical edges, as shown at f', so as to leave upper and lower lateral flanges or projections f² and f³ respectively, that are of less thickness than the rest of the plate. In the case of a type plate that is to print a character, (see Fig. 10), the upper lateral flanges f² are cut away at f²¹ for a purpose hereinafter described, and the type character is formed on the bottom of the plate at g. In the case of a type plate that is to form a "space," (see Fig. 11), the lateral flanges f² retain their width from top to bottom, for a purpose hereinafter described, and the bottom of the plate is grooved as shown at h, so that it will make no impression on paper pressed against it. In the upper portion of each type plate is a V shaped notch i the opposite edges of which are formed with a number of ribs and recesses i' that are differently

shaped or arranged for different type plates, similarly to the type plates used in line-of-type casting machines, for the purpose of enabling the different type plates to be 5 readily distributed, after being used for printing, back into the magazine receptacles *a*.

The type plates *f* are arranged one above another in their respective type receptacles 10 *a* and their descent in such receptacles is controlled by corresponding escapement devices by means of which they are allowed to fall, one at a time, and pass to the type 15 assembling means. For this purpose, each escapement device may be adapted, when in one position, normally to engage and hold the lowermost type plate in the corresponding receptacle and thus to support the whole 20 column of type plates in that receptacle but when moved into another position by its corresponding selective type lever, it will engage and hold the next upper or penultimate type plate and release the lowermost type plate and when moved into another 25 position, it will release the penultimate type plate, which now becomes the lowermost type plate, and reengage and hold it when it assumes its lowest position in the receptacle.

30 In the arrangement shown for this purpose, each escapement device comprises a two armed lever *k* (see Figs. 3 and 4) mounted to turn in a vertical plane about a horizontal spindle *m* and provided at its 35 upper and lower ends with horizontal pins *o* and *p* jointed to the said lever. The lever is normally held in a position in which, as shown in Fig. 3, the lower pin *p* extends into the notch *f'* in one side of the lowermost type plate *f* (Figs. 10 and 11) and engages the lower side of the upper end wall of the notch in the plate. The upper pin *o* of the escapement lever *k* is similarly arranged opposite the notch *f'* in one side of 40 the next adjacent upper type plate *f* but does not extend into such notch. The escapement lever is suitably connected, as by a link *r*, to the associated selective type lever *B*. This lever is mounted to turn upon a 45 spindle *t* and is actuated by the piston and piston rod *J* of a pneumatic motor the cylinder *H* (see Fig. 2) of which is formed in a stationary block *I* as hereinbefore described. Each selective type lever *B* and 50 associated escapement lever *k* are normally held in the position shown in Figs. 3 and 4 by a spring *u*. *v* is a vertical comb shaped plate for separating and guiding the horizontal end portions of the selective type levers *B*. The arrangement is such that when 55 a selective type lever *B* is operated in one direction by its pneumatic motor *H*—*I*, under the action of the selective mechanism of the electric impulse or perforated tape 60 controlled machine to reproduce a character

ter in ordinary printed form, the corresponding escapement lever *k* will be turned in one direction to cause its upper pin *o* to engage and hold the penultimate type plate *f* and its lower pin *p* to release the 70 lowermost type plate *f*. When the selective type lever *B* returns to its normal position, under the action of its spring *u*, the escapement lever *k* will be moved in the opposite direction into its normal position in 75 which its upper pin *o* will release the type plate with which it was engaged and allow this plate to fall, and will simultaneously move the lower pin *p* into a position to arrest and hold the said plate in the lowermost position until the corresponding selective type lever *B* is again actuated when the above described operations of the escapement lever *k* will be repeated to again 80 release the lowermost type plate. 85

The line of type assembling means comprises, according to the arrangement shown, the vertical channel *e'*, the bottom *e*² of which forms a support for each type plate *f* falling on to it, a stationary horizontal bar 90 1 of V shape in cross section, at its lower part which is formed on its opposite side with ribs and grooves 1^a adapted to fit the grooves and ribs in the edges of the V shaped notches *i* (Figs. 10 and 11) of the 95 type plates *f*, and a pair of horizontally movable pins 2 carried by a crosshead 3 and arranged to work through holes in the side walls of the channel *e'* and act upon a type plate *f* therein and force it laterally on to 100 the V shaped portion 1^a of the bar 1. The cross head 3 is arranged to slide between stationary guide bars 4 and is reciprocated by a rod 5 from a crank disk 6. This disk is fixed on the main driving shaft *M* so that 105 it makes one rotation for each rotation of the main driving shaft *K* of the Creed selective apparatus. The type plates *f* as they are assembled are gradually moved along the bar 1 and are finally arrested by a movable stop 7, (Fig. 2) thus forming a line of 110 type as shown at *f*, (Fig. 1) that may be of a given maximum length, or of less length, before they are used for the printing of a line of ordinary characters on a sheet of paper, the type characters being on the bottom of the type plates as shown at *g* in Fig. 10. The line of type plates are pressed against the movable stop 7 by a pusher comprising, in the example shown, a pair of 115 spring fingers 8 carried by a stirrup shaped carrier 9 arranged to slide on the horizontal bar 1 and to be moved to and fro thereon by two flexible connectors 10 and 11 respectively connected to opposite sides thereof. 120 The connector 10 is led around guide pulleys 12 and connected at its other end to a winding drum 13 (Figs. 1, and 4) mounted to rotate on the main driving shaft *M* and driven therefrom through a friction clutch one 125 130

member 14 of which is connected to the drum 13 and the other member 14^a of which is mounted to slide endwise on a tubular extension 14^b of the member 14 and is connected to an endwise movable grooved collar 15 keyed or feathered to the shaft M so as to rotate therewith. The clutch member 14^a is moved toward and from the clutch member 14 by a clutch lever 17 fixed on a 10 rock shaft at 17^a that is provided with a lever arm 17^b connected to one end of a link 18 the other end of which is connected to a swing arm 19 pivoted at 20. The link 18 is provided with a roller 21 extending into a 15 cam shaped groove 23 formed in one face of a disk 24 fixed on a slow moving cam shaft 27 (Figs. 6 and 7) that is arranged co-axial with and to the shaft N. The connector 11 is connected to a spring drum 25 the coiled spring of which is arranged within a fixed 20 casing 26.

The cam shaft 27 is rotated at determined times from the constantly rotating secondary shaft N for operating the cam disk 24 and other cams fixed thereon and hereinafter described. For this purpose upon one 25 end of the shaft N is fixed a ratchet wheel 28 and upon the adjacent end of the cam shaft 27 is fixed a plate 29 upon which is pivoted at 29^a a clutch lever one arm 30 of which is formed with a tooth 30^a and the other arm 31 of which is normally held in the position shown in Fig. 7 by a catch 32 mounted on a spindle 33 and provided with 30 a spring tongue 34. The arrangement is such that normally the clutch lever 30 and 31 is held in the inoperative position shown in Fig. 7, against the action of a spring 36 but when the catch 32 is momentarily lifted, 35 as hereinafter described, the clutch lever is released and its toothed arm 30 caused to engage the ratchet wheel 28 so that it and the plate 29 and the cam shaft 27 are caused to make one revolution at the end of which 40 the lever arm 31 is again arrested by the catch 32, the lever arm 30 disengaged from the ratchet wheel 28 and the cam shaft 27 stopped until the catch 32 is again lifted, when the described operations are repeated. 45 35 is a back stop on the plate 29 for the lever arm 31. The spring tongue 34 serves to retain the said arm 31 in the catch until the latter is lifted.

The catch 32 is lifted, for the purpose 50 described, each time the full number of type plates *f* have been assembled on the assembling bar 1, to form a line of type plates of maximum length. For this purpose there is mounted on a shaft 37 carried in 55 stationary bearings 37^a, (see Figs. 8 and 9) a ratchet wheel 38, the number of teeth on which corresponds to the predetermined 60 number of type plates *f* required to form a full line of type, say fifty five, in a printed 65 line of ordinary characters. Engaged with

this ratchet wheel is a pawl 39 carried by a lever arm 40 by a boss 41 mounted to rock on the shaft 37 and provided with another lever arm 42. The outer end of this arm 42 is connected by a link 43 to a bell crank 70 lever arranged to be oscillated about an axis at 44 by a rotary cam 45 on the main driving shaft K. The arrangement is such that the ratchet wheel 38 will be fed forward one tooth for each rotation of the driving 75 shaft K and therefore for each type plate *f* fed on to the assembling bar 1. On one face of the ratchet wheel 38 is a tooth 46 arranged to engage one arm 47 of a bell crank lever pivoted at 48^a and the other 80 arm 47^a of which is arranged to lift a bar 49 each time the ratchet wheel has moved through a distance corresponding to the whole of the teeth thereon, say fifty five teeth. 50 is a detent pivoted to a fixed part 85 of the apparatus and engaged with ratchet wheel 38. The bar 49 is provided with a projection or tappet 51 adapted, when the bar is raised, to engage a projection 32^a on the pivoted catch 32 (Figs. 6 and 7) and 90 thus to raise the catch and to release the clutch lever 30—31 to enable it to engage the ratchet wheel 28 and cause the cam shaft 27 to be rotated from the secondary shaft N through one revolution. The catch 32 95 will then disengage the clutch lever 30—31 from the ratchet wheel 28, whereupon the cam shaft will be stopped and remain at rest until the catch 32 is again lifted after another revolution of the ratchet wheel 38. 100 To prevent the bar 49 falling too quickly, that is to say before the catch 32 has properly released lever 30—31, there is pivoted to the bar 49, a stop 52 in the form of a lever, one arm of which, under the action 105 of a spring 53, is caused to rest upon a fixed support 54, when the bar is raised, and which is afterward disengaged from the said support by a pin 45^a on one end of the cam 43 to allow the bar to fall into its 110 normal position.

When it is desired to enable the cam shaft 27 to be connected to the secondary shaft N before the ratchet wheel 38 has completed a full revolution corresponding to a full 115 length line of type plate, as for instance when it is desired to print an address containing a less number of type characters than that in a full length line of type, or a short line of characters, the bar 49 is 120 lengthened as shown in Fig. 9 and connected to a special selecting lever B' adapted to be operated by what is known as a BT, or SN signal, or other signal in the perforated type dealt with in the Creed 125 or other selective apparatus used, for indicating a short line. In this case the pawl 39 and detent 50 are provided with extensions 39^a and 50^a respectively that take into recesses 49^b and 49^c respectively in the bar 130

49 so that when this bar is lifted by the special selecting lever B', the pawl and detent are disengaged from the ratchet wheel 38 which, in each case, is caused to return, 5 under the action of a spring in a stationary spring drum 55, to an initial starting position that is determined by an arm 56 connected to the ratchet wheel coming into contact with a fixed stop 57. The same action will also take place when the bar 49 is raised by the lever 47-47^a under the action of the pin 46 on the ratchet wheel 38.

Also, in this case the bar 49 is made in two lengths the lower of which is normally held on the arm 47^a of the lever 47-47^a 15 by a pawl 47^b carried by one end of a rod 48 and arranged to bear upon a shoulder 49^a on the said lower part of the rod 49. The rod 48 is arranged to slide endwise in a 20 stationary bearing and is formed with a slot 48^a through which extends a pin 48^b carried by the lever arm 47 to which the second end of the rod 48 is connected by a spring 48^c. The arm 47^a in this case is, as 25 shown, preferably made as a spring blade. With this arrangement the upper part of the rod 49 can be raised by the special selecting lever B' for the purpose mentioned, without raising the lower part or affecting 30 the lever 47-47^a and attached parts. When however the wheel 38 makes a complete revolution and causes the tooth 46 to act against the lever arm 47, it will stress the spring blade arm 47^a, until the pin 48^b on 35 the arm 47, by acting against one end of the slot 48^a, moves the rod and pawl 47^b out of engagement with the shoulder 49^a on the lower part of the rod whereupon the 40 whole rod is caused to rise quickly and close the clutch on the shafts N and 27. This mechanism is hereinafter sometimes referred to collectively as type counting mechanism.

When the cam shaft 27 is rotated by the shaft N as described, the cam disk 24 will 45 act through the link 18 (Fig. 4) to close the friction clutch 14-14^a so as to rotate the winding drum 13 and wind up the flexible connector 10 so as to move the carrier 9 along the type assembling bar 1 along which 50 it is guided by lateral pins 9^a working in grooves 1^b in the bar, and cause the pair of fingers 8 to act upon the flanges f² of the rearmost space plate f on the bar and force the line of type plates firmly against the 55 removable stop 7 and hold it in position for printing, the said friction clutch 14-14^a then slipping.

58 is a printing roller for supporting a sheet of paper 59 below the line of type 60 plates at f^x held on the bar 1 (Fig. 1) in readiness for printing. The roller is carried in bearings in the forked arm 60 of a lever pivoted at 60^a and the other arm 61 of which is arranged to be depressed, at the 65 right time, by a cam 62 fast on the cam

shaft 27 so as to raise the printing roller and cause the sheet of paper 59 to come into contact with the underside of the line of type bars at f^x for printing a line of ordinary characters thereon, the roller with 70 paper being afterward returned to its lower and normal position by a spring 62^a connected to the lever arm 60. The sheet of paper 59 is drawn from a roll 63 thereof over the printing roller 58 and under guide 75 rollers 64 and upward over a fixed support 65 so that the line of printed characters can be readily seen and read. For feeding the sheet of paper forward, it is provided at 80 intervals along its edge with holes to engage corresponding pins 66 on the printing roller 58 which is rotated through a small angle by a pawl 67, each time it is moved downward by the lever arm 60, the said pawl 67 being pivoted to part of the fixed 85 support T and engaging a ratchet wheel 67^b on the roller. Backward rotation of the printing roller is prevented by a detent 68 pivoted to the lever arm 60.

The type characters on the lower ends of 90 the type plates may be inked by passing over the periphery of inking wheels 69 as they are fed along the bar 1. Or an inking ribbon may be arranged between the printing roller 58 and the line of type plates f 95 when this is held in the printing position f^x against the removable stop 7. The removable stop 7 is withdrawn from the line of type plates, after the printing operation, by arms on a link 70 operated by a lever arm 100 71, that is fixed on a spindle 72 to which is also fixed another lever arm 73 carrying a roller that extends into a suitably shaped cam groove 74^a in one side of a cam disk 74 fixed on the cam shaft 27. 105

When the stop 7 is withdrawn, after the printing operation, the friction clutch 14-14^a which had been slipping will at once come into action again and move the line of type plates endwise to a farther extent sufficient to transfer it from the assembling bar 1, to a vertically movable carrier 76 (Figs. 1, 2, and 3), by which it is transferred to a position to be delivered to the type distributing mechanism at E. The carrier 76 is a bar of V shape in cross section and formed on its opposite sides with ribs and grooves 76^a adapted to fit the grooves and ribs in the edges of the V shaped notches i in the upper edges of the type 120 plates f. This carrier, when held in its lowermost position, is in line with the V shaped recesses i in the line of type plates f carried by the assembling bar 1 so that these plates can, after printing, be pushed off the 125 bar 1 and on to the carrier 76 so as to be left suspended from the latter.

In the arrangement shown, the means used for transferring each line of type plates from the assembling and printing position 130

to the distributing position, comprises a pair of vertically arranged intermittently operated endless bands 77 that pass over and under upper and lower pairs of pulleys 78 and 79 fixed on shafts 80 and 81 respectively and to which are attached, transversely, a number, conveniently three, of type carriers 76 of the kind hereinbefore described. The arrangement is such that in each of three 10 positions of the pair of belts there is a carrier 76 in the lowermost position opposite the type assembling bar 1, another opposite the supporting bar 82 of the type plate distributing mechanism at E, and another 15 at an intermediate position, on the descending side of the bands 77.

The bands 77 are provided with holes 84 for engagement with spaced projections 85 on the band pulleys 78 and 79 to keep the latter in register. The shaft 80 for the upper pair of pulleys 78 is arranged to be driven through a friction clutch (see Fig. 2) one member of which, namely 86, is fixed to the shaft 80 and the other member 87 of which is mounted to turn on the shaft. The clutch member 87 is constantly rotated from the main driving shaft K through a pulley 89 and a cross belt 91 and is constantly pressed against the first member 86 by a coiled spring 86^a. The arrangement is such that the conveyer bands 77 and pulleys 78 and 79, can be held stationary, when required, without stopping the clutch member 87, the clutch then slipping and can, when released, be again set in motion through the said clutch 86—87.

For arresting the endless conveyer 77 so as to hold one carrier 76 in line with the assembling bar 1 to allow of the transfer of 40 a line of type plates from this to the said carrier and to hold another carrier 76 with a line of type suspended therefrom in line with the stationary bar 82 of the type distributing mechanism at E, there is provided 45 in the arrangement shown, a bell shaped stop lever 92 pivoted at 92^a and the upper end of which can be moved, at the required time, into a position below an empty intermediate carrier 76 to arrest the downward movement thereof and attached parts for the desired period. For this purpose the lever 92 is connected by a link 93 to a lever arm 94 pivoted at 94^a and arranged to be raised by a cam disk 95 fixed on the cam 50 shaft 27. The movement of the stop lever 92 into its inoperative position is also effected by the cam disk 95.

The type plate distributing mechanism shown at E comprises the stationary supporting bar 82 which is of V shape in cross section and formed with longitudinal ribs and grooves adapted to engage the notched or toothed sides of the V-shaped recesses *i* in the upper ends of the type plates *f*, the ribs 60 on the bar being cut away at different parts

of their length in order to adapt them, in the known way to release each type plate when it is brought over its proper receptacle *g* in the magazine A. The type plates are moved along the supporting bar 82 by a pair 70 of constantly revolving screws 96, arranged horizontally at opposite sides of the supporting bar 82, and above the magazine and engaging the opposite edge portions of the type plates *f*. The screws may advantageously be made of increasing pitch from left to right (Fig. 1) so as to separate the type plates from each other, as they travel along the supporting bar 82, to facilitate their falling clear of the screws at the required time. 75 In the example shown, the two screws are geared together by toothed wheels 97 and one of them is driven from the main driving shaft K through pulleys 98 and 99 and an endless driving band 100. Below one of the screws 96 is another screw 96^a to engage 80 the lower portion of the type plates *f*, to support and guide them laterally.

The means used, in the apparatus shown, for transferring a line of type plates *f* from each carrier 76 to the supporting bar 82 comprises a block 101 mounted to slide on stationary horizontal guide bars 102 and to be moved to and fro by two flexible connectors 103 and 104. The connector 103 is 90 arranged to pass around guide pulleys 105 and to be wound up by a spring drum 106; the connector 104 passes around a guide pulley 107 and is arranged to be wound up by a winding drum 108. This drum 108 is 95 driven, at the required time, through bevel gearing 109 and one member 110 of a toothed clutch from the other clutch member 111 which is feathered on a shaft 112 which extends freely through and supports the 100 clutch member 111 and corresponding clutch member 110 and bevel wheel 109. The shaft 112 is the one constantly rotated from the main driving shaft K through pulleys 98 and 99 and the endless band 100. The clutch member 111 is normally held in the open 105 position by a clutch lever 116 under the action of a spring 117. It is moved endwise into the closed position, to rotate the winding drum 108, by an electro-magnet 118 the 110 circuit of which is closed at the required time by the insertion between a pair of spring contact fingers 119 of a circuit closing or switch contact 120, the electro-magnet 118 being arranged to attract the free end of the 115 clutch lever 116 which is adapted to act as an armature. The switch contact 120 is withdrawn from the fingers 119 to open the circuit and permit the clutch lever 116 to open the clutch 110—111 under the action 120 of the spring 117 when it is desired to stop the winding drum 108. 116^a is a stop for the clutch lever. The movable switch contact 120 is carried by a switch lever 121, that is pivoted at 122^a and is arranged to be 125 130

5 moved into the circuit closed position by a pusher 123 fixed to the slide block 101 and into the circuit open position by a tappet 124 fixed at a suitable point in the length of the flexible connector 104. The switch lever is 10 normally held supported by a jockey pulley 125, in each of the positions into which it is moved.

To enable the spring drum 106 to come 15 into action to move the slide block 101 to the right (Fig. 1), only when a carrier 76 with a line of type and plates *f* suspended therefrom comes into correct alinement with the stationary bar 82, the slide block 101 is 20 normally held in its left hand position by a lever catch 126 pivoted to a stationary support 127 and adapted normally to engage with a notched part 128 of the block under the action of a spring actuated pin 128^a carried 25 by a fixed support 129. The catch 126 is arranged to be disengaged from the block 101 to release the same, by a pin 130 that is arranged to be moved endwise through a fixed support 131 by the adjacent end of 30 each carrier 76 when such carrier comes into correct alinement with the stationary bar 82. The arrangement is such that normally the block 101 is retained in its left hand position (Fig. 1) against the pull of the spring 35 drum 106 by the catch 126. When an ascending carrier 76 comes into correct alinement with the supporting bar 82, the catch 126 is tripped by the pin 130, under the action of the carrier. At the same time the 40 motion of the endless conveyer bands 77 with carriers 76 thereon, is arrested by the bell crank lever 92 being brought into the path of the descending intermediate empty carrier 76 (Fig. 3) through the action of the 45 cam 95. The spring drum 106 then acts through the flexible connector 103 to move the block 101 to the right, and force the line of type plates off the uppermost carrier 76 and along the horizontal bar 82 and into engagement 50 with the distributing screws 96 by which they are moved over the receptacles *a* in the magazine A into which the types fall when brought over their proper receptacles and thus distributed for re-use. When the 55 block 101 has moved the last type plate *f* in the line of type plates into a position to be engaged by the screws 96, the pusher 123, by acting on the switch lever 121 forces the movable contact 120 between the contact fingers 119 and thus closes the circuit of the 60 electro-magnet 118. The lever 121 is then held in the operative position by the jockey pulley 125. The magnet by then acting on the clutch lever 116 closes the clutch 65 110—111 and thus brings the winding drum 108 into action to wind up the flexible connector 104 and return the block 101 to its initial left hand position in which it is again held by the spring actuated catch 126.

65 At this moment the tappet 124 on the said

flexible connector 104 acts against and moves the switch lever 121 into its open position thereby withdrawing the movable contact 120 from between the spring contact fingers 119 and demagnetizing the electro-magnet 118, thus permitting the spring 117 to open the clutch 110—111 and slipping the winding drum 108. The switch lever 121 is then again held in its open position by the jockey pulley 125.

The operation of the whole apparatus is as follows:—Assuming the Creed selective apparatus to be in action, then type plates *f* will be released one at a time from the receptacles *a* in the magazine A by the type 80 selective levers B and allowed to fall into the guide channel *e*¹ from which they will be forced by the pushers 2 on to the stationary assembling bar 1 until either a full length line of type plates, or a less length 85 of line of type plates, has been assembled thereon, according as to whether the ratchet wheel 38 has been allowed to make a complete rotation without the operation of the special selective lever B¹, or has been allowed to make less than a complete rotation by the operation of this special lever as hereinbefore described. In either case the clutch lever 30—31 (Fig. 7) is released by the catch 32 and the cam shaft 27 rotated through one 90 revolution from the secondary shaft N, whereupon the clutch lever is moved into the inoperative position by the said catch 32 and the cam shaft 27 brought to rest. During the rotation of the cam shaft 27 the 95 cam disk 24 acts, as hereinbefore described, to close the friction clutch 14, 14^a and cause the winding drum 13 to wind up the flexible connector 10 and thereby move the pair of 100 fingers 8 to the left (Fig. 1), the said 105 fingers acting against the flanges *f*² of the rearmost "space" plate *f* on the assembling bar 1 and forcing the line of type plates *f* on this bar forward into the printing position and against the movable stop 7 by which 110 it will be arrested. The friction clutch 14—14^a, although still closed will then merely slip idly. Should the type characters *g* on some of the type plates at the right hand or rear end of the line of type plates 115 form an incomplete word, the fingers 8 will pass idly through the notches *f*²¹ (Fig. 10) in the flanges *f*² of the said type plates until they meet the unnotched flanges *f*³ (Fig. 11) of the rearmost "space" type plate *f* and 120 act against the same to force such type plate and the character type plates in front of it forward against the movable stop 7. In this way the line of type plates *f* forced into the printing position will form only complete 125 words.

The cam 62 and lever 60—61 will then come into action to raise the printing roller 58 against the action of the spring 62^a to bring the sheet of paper 59 thereon against 130

the line of type characters g at the bottom of the line of assembled type plates f to print a line of ordinary characters on the sheet. The cam 62 then releases the lever 5 60—61 and allows the printing roller 58 and sheet of paper to descend under the action of the spring 62^a and is at the same time rotated forward a step by the pawl 67 to bring the sheet of paper into position 10 to receive the next line of printed characters. The movable stop 7 is then withdrawn from in front of the line of assembled type plates f by the cam disk 74 whereupon the still closed friction clutch 14—14^a 15 which had been slipping, again acts to rotate the winding drum 13 and further wind up the flexible connector 10 to a sufficient extent to cause the fingers 8 to push the line of type plates f off the assembling bar 20 1 on to the lowermost carrier 76 which at this time is held in alignment with the said bar by the stop lever 92 which at this time is held in its operative position by the cam 95 so as to act against the under- 25 side of the empty intermediate carrier 76 (Fig. 3) that is on the descending side of the endless conveyer bands 77. The cam disk 95 then acts to withdraw the stop lever 92 from below the said intermediate carrier 76 and the friction clutch 86—87, 30 which had previously been slipping, will act to drive the shaft 80 and operate the endless conveyer bands 77 to lift the lowermost carrier 76 with line of type plates 35 thereon, to a position opposite the supporting bar 82 and the carrier 76 that was previously the intermediate empty carrier, will have been brought into its lowest position in alignment with the assembling bar 1. 40 During this motion the cam disk 95 will move the stop lever 92 into the operative position shown in Fig. 3 in which it will again arrest the endless conveyer bands and hold the three carriers 76 in the positions 45 mentioned, the friction clutch 86—87 again slipping idly. The cam shaft 27 carrying the several cams 24, 74, 62 and 95 having made one revolution will be unclutched from the secondary shaft N. When the carrier 76 with the used line of type plates 50 thereon, reaches its uppermost position in line with the supporting bar 82, the slide block 101 will be released by the operation of the catch lever 126 and the line of type plates will be moved along the said bar to the type distributing mechanism and distributed into the type plate receptacles a 55 in the magazine A in the manner hereinbefore described. Meanwhile a fresh line of type plates f will have been assembling on the bar 1 until the catch 32 (Fig. 7), under the action of the toothed wheel 38, or special selective lever B¹, again releases the clutch lever 80—81 and again connects the

cam shaft 27 to the secondary shaft N when 65 the above described operations will be repeated to print another line of words on the sheet below the first line. In this way successive lines of words can be printed in a column on the sheet of paper. 70

As will be obvious, the details of construction can be variously modified without departing from the essential features of the invention.

Also it will be obvious that instead of 75 printing successive lines of ordinary characters by the lines of type on paper or like material as hereinbefore described, the lines of type can be used to impress successive lines of ordinary characters in a sheet of 80 flong from which a stero plate can be cast for use in printing on paper.

What we claim is:—

1. Apparatus of the kind referred to, comprising, in combination, a type magazine, type assembling means associated therewith, automatically operated selective means adapted to permit of the release and passage of types singly from the magazine to the assembling means, paper holding, 85 feeding and printing mechanism, and means whereby a line of assembled types is moved bodily to the latter, for the purpose specified. 90

2. Apparatus of the kind referred to, comprising in combination, a type magazine, type assembling means associated therewith, automatically operated selective means adapted to permit of the release and passage of types singly from the magazine to the assembling means, paper holding, 100 feeding and printing mechanism, means whereby a line of assembled types is moved bodily to the latter, type distributing means associated with a type magazine and means 105 whereby the line of type after the paper has been printed therefrom is transferred to the said type distributing means and a motor driven main shaft from which the movable parts of the apparatus derive motion at the required times. 110

3. Apparatus of the kind referred to, comprising type selecting levers, means for automatically operating said levers, a multi-channelled type magazine containing the different kinds of type to be used, type delivering mechanism operated by or under the control of the type selecting levers and adapted to cause selected type to pass one at a time from their respective receptacles, line 115 of type assembling means whereby released type are assembled in the form of a line of type representing one or more words with one or more spaces between words, a movable carrier for a line of type, means for 120 transferring a line of type from the assembling means to the said carrier, a platen for carrying a sheet of paper upon which 125

the line of type is caused to print or impress a line of words before being transferred to the carrier, means for moving the platen with sheet of paper relatively to the line of type so as to cause the latter to print or impress a line of words on the sheet of paper, means for feeding the sheet of paper endwise so that successive lines of words can be printed or impressed in column form 5 thereon, type distributing mechanism arranged above the magazine, carrier transferring means whereby the carrier with the line of type carried thereby, can, after it has printed or impressed a line of words, be 10 brought into a position for the line of type to be transferred to the type distributing mechanism, means for transferring the line of type from the carrier to the distributing mechanism, and motor operated mechanism 15 for automatically actuating, at the required times, the various parts of the type releasing means, type assembling means, printing or impressing mechanism and carrier transferring means necessary for effecting the 20 above mentioned operations.

4. In apparatus of the kind referred to, the combination of a multi-channeled type magazine having a single outlet, Creed selective apparatus adapted automatically to release type one at a time from said magazine, a type receptacle in communication with said outlet and having a lateral opening through which a type can be displaced horizontally and at right angles to said channel, 30 a stationary horizontal bar in register with such opening and a horizontal reciprocating member at the opposite side of the channel having pins adapted to traverse the channel and transfer a type from the latter on 35 to the stationary bar aforesaid.

5. In apparatus of the kind referred to, the combination of a stationary type supporting bar, a shaft adapted to be continuously operated, type assembling means comprising a pusher adapted to be continuously reciprocated from said shaft and to successively feed types one at a time on to such bar, means under the control of said shaft adapted to move a line of types as a whole 45 along such bar and a stop adapted temporarily to arrest such line of type in a printing position and to be afterward moved by said shaft into a position to release said line of type.

55 6. In apparatus of the kind referred to, the combination of a multiple type magazine, automatically operated type releasing means, type assembling means, a stationary type supporting bar, a type distributing bar above said magazine, a main rotary driving shaft, means adapted to be operated intermittently from said shaft and adapted to move a line of type as a whole along said supporting bar, and conveying means, oper-

ated intermittently from such driving shaft 65 and adapted to receive the line of type from said supporting bar and carry it to the type distributing bar, the said line of type being transferred from the supporting bar to the type conveying means by the means that 70 move the line of type bodily along the supporting bar.

7. In apparatus of the kind referred to, the combination with a stationary type supporting bar, a type distributor, a conveyer 75 between the said bar and the distributor and means adapted to move a line of type bodily along and off such bar in to the conveyer, of means adapted to temporarily arrest the line of type in printing position before the 80 conveyer is encountered.

8. In apparatus of the kind referred to, the combination with a type supporting bar, of a pusher adapted to move a line of type 85 as a whole along such bar, spring means adapted to hold the pusher in initial position and return it thereto when necessary, and means embodying a clutch and continuously rotating shaft whereby the pusher can be intermittently moved, in opposition 90 to the spring returning means, from such shaft.

9. In apparatus of the kind referred to, the combination with a type supporting bar, and a conveyer associated therewith, of a 95 pusher adapted to move a line of type as a whole along such bar and transfer it to the conveyer, means adapted to temporarily arrest such line of type at a printing position and driving means for such pusher embodying a continuously rotating shaft and a friction clutch adapted to slip when the line of type is temporarily arrested.

10. In apparatus of the kind referred to embodying a supporting bar for a line of 105 type, a pusher adapted to move such line of type as a whole along said bar embodying a stirrup and fingers, the latter occupying positions parallel to and at opposite sides of the supporting bar.

11. In apparatus of the kind referred to, embodying a supporting bar for a line of type and a pusher provided with fingers occupying positions parallel to and at opposite sides of the supporting bar, type plates 115 of which those representing spaces have flanges adapted to be engaged by the spring fingers of the pusher while the remainder representing characters are notched in the path of such fingers, whereby the line of type can be advanced only through the agency of a "space" type plate, thus eliminating incomplete words.

12. In apparatus of the kind referred to, embodying a type magazine, a bar for supporting a line of type, means for assembling types upon the latter and pushing means adapted to move a line of type as a whole 125

along such bar, a continuously rotating main shaft operating the type assembling means, a continuously but slower driven secondary shaft, a cam shaft, a clutch between the cam and secondary shafts, devices whereby the pushing means can be operated from the main shaft, a friction clutch connecting such devices to the said shaft, means for operating such friction clutch from the cam shaft, and means adapted to close the clutch between the secondary and cam shafts automatically after a predetermined number of revolutions of the main shaft dependent upon the number of types to be assembled in a line.

13. In apparatus of the kind referred to, the combination with means for advancing as a whole a line of assembled types, of a continuously rotating main shaft, a secondary shaft driven from the latter at a lower speed, a cam shaft, means adapted to place the cam shaft in driven connection with the secondary shaft during one revolution of the latter, a friction clutch associated with the main shaft and with the means for advancing the line of type, and means controlled by the cam shaft whereby the friction clutch is closed and opened during a single revolution of such shaft.

14. In apparatus of the kind referred to, the combination with means for advancing as a whole a line of assembled types, of a continuously rotating main shaft, a secondary shaft driven from the latter at a lower speed, a cam shaft, means adapted to place the cam shaft in driven connection with the secondary shaft during one revolution of the latter, a friction clutch associated with the main shaft and with the means for advancing the line of type, means controlled by the cam shaft whereby the friction clutch is closed and opened during a single revolution of such shaft and means also controlled by the said cam shaft adapted to temporarily arrest the line of type while the friction clutch is closed, thereby causing the latter to slip.

15. In apparatus of the kind referred to, the combination with a main, a secondary, and a cam shaft, of means continuously driving the secondary from the main shaft at a lower speed, a clutch between the secondary and cam shafts, counting mechanism, means whereby the said mechanism is operated from the main shaft once during each revolution of the latter, and means whereby the clutch aforesaid is closed through the counting mechanism when the main shaft has performed a predetermined number of revolutions corresponding to the number of types to be assembled in a line.

16. In apparatus of the kind referred to, the combination with a main, a secondary, and a cam shaft, of means continuously driv-

ing the secondary from the main shaft at a lower speed, a clutch between the secondary and cam shafts, and means whereby the clutch can be closed at any time to determine the number of types to be assembled in a line.

17. In apparatus of the kind referred to, the combination with a main, a secondary and a cam shaft, of means continuously driving the secondary from the main shaft at a lower speed, a clutch between the secondary and cam shafts, counting mechanism, means whereby the said mechanism is operated from the main shaft once during each revolution of the latter, means whereby the clutch aforesaid is closed through the counting mechanism when the main shaft has performed a predetermined number of revolutions and means whereby the clutch can be closed upon performance of a fewer number of revolutions depending upon whether a full or a short line of type is to be made up.

18. In apparatus of the kind referred to, a cam shaft, a shaft coaxial therewith, a tooth clutch member on the latter, a pawl clutch member on the cam shaft, a pivoted catch adapted normally to hold the pawl clutch member out of engagement with the tooth clutch member and arrest the cam shaft, and means for moving the arresting catch to liberate the pawl clutch member and cause the cam shaft to be driven from the companion shaft when desired, the said catch moving means quickly releasing the catch so that it reengages the pawl clutch member in order to open the clutch and arrest the cam shaft at the end of a single revolution.

19. In apparatus of the kind referred to, a pair of aligned shafts, a clutch therefor and a clutch controlling catch, a member adapted to be reciprocated and to trip the clutch catch, and step-by-step counting mechanism adapted to move the tripping member after a predetermined number of step-by-step movements.

20. In apparatus of the kind referred to, a pair of aligned shafts, a clutch therefor and a clutch controlling catch, a member adapted to be reciprocated and to trip the clutch catch, step-by-step counting mechanism adapted to move the tripping member in one direction after a predetermined number of step-by-step movements, and means operable at will for moving the tripping member in the same direction at any time.

21. In apparatus of the kind referred to, a longitudinally movable member adapted to indirectly secure clutch closure, a toothed disk, means embodying a pawl and detent for imparting step-by-step movement thereto, a spring drum opposing rotation of the disk and means whereby the disk as soon as

it completes a predetermined angular movement, is caused to displace the longitudinally movable member for the purpose specified, the said member at the same time 5 releasing the pawl and detent from the toothed disk and permitting the latter to be returned to initial position under the action of the spring drum.

22. In apparatus of the kind referred to, 10 a longitudinally movable member adapted to indirectly secure clutch closure, a toothed disk, means embodying a pawl and detent for imparting step-by-step movement thereto, a spring drum opposing rotation of the 15 disk and means whereby the longitudinally movable member can be displaced at any time for the purpose specified, the said member also releasing the pawl and detent from the toothed disk and permitting the latter 20 to be returned to initial position under the action of the spring drum.

23. In apparatus of the kind referred to, a longitudinally movable member adapted to indirectly secure clutch closure, a toothed 25 disk, means embodying a pawl and detent for imparting step-by-step movement thereto, a spring drum opposing rotation of the disk, means whereby the disk as soon as it completes a predetermined angular 30 movement, is caused to displace the longitudinally movable member for the purpose specified, the said member at the same time releasing the pawl and detent from the toothed disk and permitting the latter to be 35 returned to initial position under the action of the spring drum and means whereby the displacement of the member aforesaid can be obtained at any time independently of the angular movement of the toothed disk.

40 24. In apparatus of the kind referred to, the combination with a longitudinally movable member and a toothed counting disk adapted to displace the latter, of means whereby the motion referred to is transmitted abruptly comprising a retaining pawl normally holding the longitudinally movable member stationary, a lever having a spring arm contacting with the member aforesaid, a device upon the toothed wheel 45 adapted to displace the lever and stress its spring arm and means adapted to withdraw the retaining pawl as soon as the spring has been sufficiently stressed and permit the required movement of the first named member.

55 25. In apparatus of the kind referred to, the combination with a clutch controlling catch, and counting mechanism embodying a toothed disk, of a two part bar member, a tappet on one part of the bar member 60 adapted to displace the clutch controlling catch, means for moving the toothed disk in a step-by-step fashion, embodying a pawl and detent, connections between such latter elements and the bar part aforesaid, means

whereby the latter can be displaced at will 65 to release the pawl and detent simultaneously with displacement of the clutch controlling catch, and means whereby the displacement of the bar part referred to is effected abruptly from the companion bar 70 part when the toothed disk has completed a predetermined angular movement, said means comprising a retaining pawl normally holding the companion bar member stationary, a lever having a spring arm contacting with the member aforesaid, a device upon the toothed wheel adapted to displace the lever and stress its spring arm and means adapted to withdraw the retaining pawl as soon as the spring has been sufficiently stressed and permit the required 75 movement of the companion bar member.

26. In apparatus of the kind referred to, a pair of aligned shafts, a clutch therefor, and a clutch controlling catch, a member 80 adapted to be reciprocated and to trip the clutch catch in order to close the clutch, restraining means adapted to automatically prevent a return of the reciprocating member to initial position before the clutch is 85 closed, and means whereby the said restraining means are subsequently rendered ineffective.

27. In apparatus of the kind referred to, the combination with a bar for supporting 90 a line of assembled type, means urging the line of type along such bar and means for temporarily arresting such line of type, of a paper supporting roller, an intermittently driven cam shaft, means associated with the 95 latter adapted to advance the roller toward the line of type and withdraw it again and means whereby during the return movement aforesaid, the roller is angularly moved to feed the paper over the roller.

100 28. In apparatus of the kind referred to, the combination with a type supporting bar, means for assembling the line of type thereon and advancing the same therewith, of type distributing means, a type supporting 105 bar corresponding to the first named bar but associated with the distributing means, and means for periodically transferring a line of type from the first named to the second named bar.

110 29. In apparatus of the kind referred to, the combination with two type supporting bars arranged parallel to one another, of a conveyer comprising a series of carriers and means for arresting the conveyer with a carrier in register with each type supporting bar.

115 30. In apparatus of the kind referred to, the combination with two type supporting bars arranged parallel to one another, of a 120 conveyer comprising a series of carriers, means for arresting the conveyer with a carrier in register with each type supporting

bar, means whereby a line of type can be transferred from one supporting bar to one carrier while another line of type is being transferred to the other supporting bar from the companion carrier.

31. In an apparatus of the kind referred to, the combination with a conveyer having a series of type line carriers, of driving means therefor embodying a friction clutch and 10 means for temporarily arresting the conveyer and causing the clutch to slip.

32. In apparatus of the kind referred to, the combination with a conveyer having a series of type carriers, of driving means 15 therefor, a stop lever, a cam shaft and means whereby the motion of the latter is utilized to periodically insert the stop lever into the path of one of the conveyer carriers and withdraw it.

33. In apparatus of the kind referred to, the combination with type distributing means, a type supporting bar and a conveyer adapted to bring a line of type into alignment with such bar, of a type transferring block, means embodying a spring drum adapted to move the block in one direction and means adapted to move the said block in the reverse direction in opposition to the spring drum.

34. In apparatus of the kind referred to, the combination with type distributing means, a type supporting bar and a conveyer adapted to bring a line of type into alignment with such bar, of a type transferring block, means embodying a spring drum adapted to move the block in a direction toward the type distributing means, mechanism continuously driving the latter, means embodying a clutch associated with such 35 driving mechanism, adapted to return the block to initial position against the action of the spring drum, and means influenced by the block as it approaches the extreme limits of its movement adapted to close and open 40 such clutch.

35. In apparatus of the kind referred to, the combination with type distributing means, a type supporting bar and a conveyer adapted to bring a line of type into 50 alignment with such bar, of a type transferring block, means embodying a spring drum adapted to move the block in a direc-

tion toward the type distributing means, mechanism continuously driving the latter, means embodying a clutch associated with 55 such driving mechanism, adapted to return the block to initial position against the action of the spring drum, an electro-magnetic clutch operating device, a circuit for the latter comprising switch contacts, a contact 60 bridging member, yielding means adapted to hold such member in open and closed positions, means upon the block adapted to move the bridging member into circuit closing position, and a tappet on the block returning means adapted to move the bridging member into open circuit position.

36. In apparatus of the kind referred to, the combination with a type supporting bar, a conveyer adapted to bring a carrier with a 70 line of type into alignment with such bar and a block adapted to transfer the line of type from the conveyer to the said bar, of spring actuated means adapted to move the block to effect the transference aforesaid, winding 75 means for moving the block in opposite direction against the action of the spring means, a clutch associated with such winding means adapted to be closed to secure return of the block to initial position after 80 distribution of the line of type and to be then opened, and means whereby the spring actuated means is prevented from again moving the block unless another carrier of the conveyer be in alignment with the type supporting bar.

37. In apparatus of the kind referred to, the combination with a type supporting bar, a conveyer provided with a series of type line carriers and a block for transferring a 90 line of type from the latter to the bar, of means for alternately moving the block in opposite directions, a spring urged catch adapted to automatically engage the block when in normal position and hold it there 95 and means adapted to be engaged by a carrier when in alignment with the type supporting bar in order to retract the catch from the block and permit the latter to effect transference.

Signed at London, England, this 14th day of April, 1919.

ARTHUR JAMES POLLEY.
FREDERICK GEORGE CREED.
